UNITED STATES PATENT OFFICE.

MARY E. KUIK, OF RACINE, WISCONSIN.

MOTHPROOF BAG.

Application filed September 28, 1926. Serial No. 138,261.

The invention relates to garment protecting bags and provides an article which is proof against insects, dust and other deteriorating influences, and which obviates undue pressure on the garment to avoid wrinkles and the flattening of a collar or other part desired to stand out, such as ruffles and like trimmings, and which admits of ready access so that a garment may be easily and conveniently placed in position or removed from the bag.

The invention provides a bag having a flat top and bottom which hold the sides extended when the bag is unfolded and suspended, and which is open at the front and made secure when closed by suitable fastenings, the edge portions bordering upon the opening being stiffened and reenforced to sustain the fastenings and insure a close fit to exclude insects and dust.

While the drawings illustrate a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which:

Figure 1 is a perspective view of a garment protecting bag embodying the invention.

Figure 2 is a top plan view thereof.

Figure 3 is a view similar to Figure 2, of the bag inverted or as it appears from the bottom.

Figure 4 is a vertical sectional view on the line 4—4 of Figure 2, a portion intermediate the top and bottom being broken away.

Figure 5 is a horizontal section on the line 5—5 of Figure 4.

Figure 6 is a vertical transverse sectional view on the line 6—6 of Figure 2, looking in the direction of the arrows.

Figure 7 is an enlarged sectional view of the joint formed between the parts comprising the front, the same being taken on the line 7—7 of Figure 1.

Figure 8 is a detail perspective view of a corner portion of the bag, showing the initial fold.

Figure 9 is a view similar to Figure 8, after the fold has been completed.

Figure 10 is a detail perspective view showing the final step in forming the end closure.

Corresponding and like parts are referred to in the following description and designated in all the views of the drawings by like reference characters.

The bag may be constructed of any suitable material generally employed in the manufacture of moth-proof bags and usually consists of stout paper and may be of any dimensions according to the specific use for which the article is designed. The bag comprises enclosing sides such as a back, front, top, bottom and sides. The body of the bag is designated generally by the numeral 1 and is open at the front to admit of ready access when placing a garment in position or removing it from the bag. The ends of the bag are flat and reenforced and constitute the top and the bottom respectively. The sections of the front are designated by the numerals 3 and 4 and the edge portion of the section 3 bordering upon the opening is shaped to provide a double fold, as shown most clearly in Figure 7, the folds 5 and 6 being spaced apart to receive the edge portion of the section 4, which is reenforced by doubling a marginal portion upon itself, as shown most clearly in Figure 7. The reenforced edge portions of the sections 3 and 4 receive fastenings 7 by means of which said sections are made secure when closed. Any suitable fastening means 7 may be resorted to and, as indicated, the elements 7 consist of ordinary paper fasteners which are passed through reenforced eyelets formed in the folded and reenforced edge portions of the sections 3 and 4.

The upper and lower ends of the bag constituting the top and the bottom are similarly formed, each being reenforced and flat, and a detailed description of one will suffice for a clear understanding of both the top and the bottom. A strip 8 of cardboard or other stiff light material is utilized as the reenforcing means for each end of the bag. This strip is of a length and width to extend between the front, back and sides of the bag and is adhesively secured to a marginal portion of the back, as shown most clearly in Figure 8. An edge portion 9 of the bag is folded inwardly to serve as a re-

100

110

enforcement and the folded edge portion 9 corresponding to the back is folded over an edge of the strip 8, as indicated most clearly in Figure 8. The end portion of the back is folded to extend at a right angle thereto, as indicated in Figure 9, to form the end closure and the end folds 10. This is shown most clearly in Figure 9. The end portion of a side of the bag is now doubled upon itself producing the fold 11 which closes upon the fold 10 when the end portion of the front is folded to overlie the end of the bag. The folded end portion of the front is made secure by fastenings 7. It is preferred to secure the fold 10 to the reenforced end of the bag and this is effected by a suitable adhesive. The fold 11 is free so that the folded end of the front may be extended and the sections 3 and 4 opened outwardly so that unobstructed and free access may be had to the interior of the bag when placing a garment therein or removing it therefrom.

A suitable garment hanger 12 is applied to the top of the bag to admit of a garment being draped thereover and a suspending hook 13 is connected with the hanger 12 and provides means for suspending and handling the bag. Pockets 14 are located upon the inner side of the front near the top thereof to receive any determinate compound usually employed for destroying insects and thereby adding to the efficiency of the article.

Having thus described the invention, what I claim is:

1. A garment protecting bag of the character specified having a reenforcing strip attached to an end portion of the back and adapted to have end portions of the sides 40 and front folded thereover.

2. A garment protecting bag having an end portion folded inwardly, a reenforcing strip forming an end closure and attached to an end portion of the back with the edge portion folded thereover and having end portions of the sides and front folded inwardly to overlie the reenforcing strip, the folds at the ends of the sides being attached to end portions of the reenforcing strip.

3. A garment protecting bag open at the front and having edge portions of the sections comprising the front reenforced and overlapped, one of the edge portions having a double fold between which the edge portion of the other section is received and adapted to be secured, reenforcing strips attached to end portions of the back and folded inwardly at a right angle thereto and having end portions of the sides inwardly 60 folded and attached to end portions of the reinforcements, and having end portions of the front folded to overlie the reenforced end closures and retained in place by suitable fastening means.

In testimony whereof I affix my signature.

MARY E. KUIK. [L. s.]
